UNITED STATES PATENT OFFICE.

CLINTON E. LONG AND FREDERICK R. LONG, OF BERWICK, PENNSYLVANIA.

ELASTIC-FLUID TURBINE.

1,068,596.

Specification of Letters Patent. Patented July 29, 1913.

Application filed June 23, 1911. Serial No. 634,962.

To all whom it may concern:

Be it known that we, CLINTON E. LONG and FREDERICK R. LONG, citizens of the United States, residing at Berwick, in the 5 county of Columbia and State of Pennsylvania, have invented certain new and useful Improvements in Elastic-Fluid Turbines, of which the following is a specification.

Our invention relates to turbines driven 10 by elastic fluid, and the main object of the invention is to provide a very simple and efficient turbine in which the rotor is actuated by the impact of a jet of elastic fluid, and by the reaction of the fluid.

15 A further object is to provide a turbine of this character in which no valves or complicated valve gear are necessary.

A further object is to eliminate the necessity of using a close fitting casing for the 20 rotor, thus eliminating a very large amount of friction, and further in this connection to provide means for securing a steam tight engagement between the face of the rotor and the abutment or abutments which constitute or form part of the stator.

25 A further object is to provide means whereby the several abutments may be so constructed that they will each be independently forced into engagement with the 30 rotor and will wear so that the face of each abutment will correspond exactly with the face of the rotor without the necessity of providing packing strips between the abutment and rotor face.

35 A still further object is to provide a rotor so balanced as to eliminate side movement and thus eliminate unnecessary wear.

Other objects of the invention will appear in the course of the following description.

40 Two forms of our invention are illustrated in the accompanying drawings, both of which forms, however, operate on precisely the same principle.

In these drawings: Figure 1 is a vertical section on the line 1—1 of Fig. 2 45 of a turbine constructed in accordance with our invention. Fig. 2 is a section on the line 2—2 of Fig. 1. Fig. 3 is a side elevation of another form of turbine, operating however in precisely the same manner as the form shown in Fig. 1. Fig. 4 is a diagrammatic face view of the rotor showing the arrangement of pockets therein. Fig. 5 is an inside face view of one of the 55 abutments. Fig. 6 is an enlarged longitudinal diagrammatic section of a portion of the

rotor rim and of an abutment, the parts being shown in the position taken by a pocket of the rotor rim as it moves into registry with an expansion pocket in the face of the abutment. Fig. 7 is a like view to Fig. 6 but showing the position of the parts at the moment when motive fluid is being discharged into the pocket and against the forward end wall thereof. Fig. 8 is a like view to Fig. 7 but showing the position taken by the parts after the motive fluid has been cut off and while it is expanding. Fig. 9 is a like view to Figs. 6, 7 and 8 but showing the position of the parts when the rotor pocket has cleared the end of the abutment to permit the discharge of the exhausted motive fluid from the pocket. Fig. 10 is a diagrammatic section on the plane of the inlet nozzle and inlet port and showing the parts in the position illustrated in Fig. 8, that is, showing the inlet nozzle closed, the pockets in the abutment and rotor being shown in section. Fig. 11 is a transverse section on the line 11—11 of Fig. 4.

Corresponding and like parts are referred to in the following description and indicated in all the views of the accompanying drawings by the same reference characters.

In the drawings, and referring particularly to Figs. 1 and 2, 2 designates a rotor and 3 the shaft. The rotor is formed preferably with a relatively light web 4 and a relatively heavy rim 5, though we do not wish to be limited to any particular construction or form for the rotor.

The face of the rotor rim is provided with one or more circumferential series of pockets 6 having offset inlet ports 7 at one end. Preferably there are two series of pockets 95 as shown in Fig. 4, disposed in circumferential zones *a* and *c* on each side of a middle zone *b*. The inlet port 7 of each pocket is located at the forward end of the pocket and extends laterally into and across this middle 100 zone *b*. Preferably the pockets 6 of one series have a staggered relation to the pockets 6 of the other series. The pockets are preferably all of the same length and the distance between each pair of pockets of one 105 series is equal to the length of a pocket of the other series, as illustrated in the diagrammatic view, Fig. 4.

We have illustrated and described a rotor having two series of pockets, but it is to be understood that we may have a larger number of series of pockets or only one series,

it being only necessary that all the pockets of a series shall be arranged in alinement and that each pocket shall have an inlet port which extends laterally and all the inlet ports of a series shall be in line with each other.

Each pocket as shown in Fig. 1 and in Figs. 6 to 9 has a front wall 8 which preferably extends tangentially to the shaft 3 and therefore approximately at right angles to the axis of the jet of motive fluid whereby the rotor is propelled. The bottom 9 of the pocket extends outward and rearward to the face of the wheel and at substantially a right angle to the forward wall 8 thereof.

The side wall of each inlet port 7 is preferably in alinement with the inner wall of the next adjacent pocket, or in other words extends clear across the zone b , and this side wall is inwardly and laterally inclined as shown in Fig. 11 and intersects the main body of the pocket at about the middle of the depth of the pocket.

Disposed around the rotor are a plurality of abutments, designated 11 in Figs. 1 and 2, and 37 in Fig. 3. These abutments form part of the stator within which the rotor moves. Each abutment preferably consists of a block of relatively soft metal such as Babbitt metal, or a block faced on its inside face with Babbitt or like relatively soft, anti-frictional metal. We do not, however, wish to be limited to the exact shape of the blocks or to the material from which the abutments are made as they might be made of a large number of relatively soft alloys. It is sufficient if the abutments are made of material softer than the rotor rim so that the abutments will wear into close correspondence with the contour of the rotor rim. These abutments are preferably rectangular in form and the inside face of each abutment is concavely curved to accurately fit the curvature of the rim 5. By making the abutments of relatively soft metal such as Babbitt metal, we obviate the necessity of using packing between the abutment and the rotor, and we very greatly reduce friction, not only because the packing is eliminated, but also because the Babbitt metal reduces very greatly friction between the abutment and the face of the rotor. Furthermore, as the abutment wears, it conforms exactly to the contour of the face of the rotor rim and hence the abutment never requires any adjustment. Each abutment is resiliently forced inward against the face of the rim as will be later described, and hence is held in close engagement with the rim face.

Each abutment is provided with an inlet nozzle or passage 12 whose inner end is preferably tapered and extends inward and toward the forward end of the abutment at an angle to the inner face of the abutment. The axis of the inlet passage is approxi-

mately at right angles to the face of the wall 8 of any one of the pockets 6 when the pocket is in the position shown in Fig. 7. The inlet passage is in communication with a source of elastic fluid by means of a duct 13 having the form of a pipe in the embodiments of our invention disclosed in the drawings, and constitutes a discharge duct.

Formed in the face of each abutment is a pocket which is located rearward of the nozzle or inlet passage 12. If there is only one series of pockets 6, there will be only one pocket 14 in each abutment, so arranged on the abutment that it will register with the series of pockets on the rotor. As shown, however, there are two series of pockets 6 arranged on each side of the median zone b and hence the opening of the nozzle 12 will be arranged on a median line, and two pockets 14 are provided corresponding to the two series of pockets 6 and arranged one on each side of said median line in such position as to register respectively with the two series of pockets 6. Each pocket 14 has a bottom wall 15 which extends rearward and away from the concave face of the abutment, and a rear wall 16 which extends to the face of the abutment and is approximately at right angles to the wall 15. The wall 15 is therefore approximately parallel to the bottom of any pocket 6 when the said pocket 6 is in register with the pocket 14. In this position the walls 8 and 16 are also approximately parallel.

Before describing the mounting of the abutments it will be well to describe the operation of the turbine with special reference to Figs. 6 to 10. In these figures the rotor is rotating in the direction of the arrow and the abutment is of course forced against the face of the rotor by resilient pressure as will be later described.

The description of the operation with relation to one of the series of pockets will, of course, apply to both of the series. In Fig. 6 the rotor is shown as having arrived at a position in which one of the pockets 6 is moving into register with the corresponding pocket 14 on an abutment. The inlet port 7 of the pocket has not yet arrived in register with the discharge opening in the inlet nozzle 12.

In Fig. 7, the rotor has moved sufficiently to carry the inlet port 7 into register with the inlet nozzle 12 and motive fluid is being discharged into the pocket 6, and particularly against the wall 8 of the pocket.

In Figs. 8 and 10, the rotor has moved so far forward that the metal 17 of the face of the rotor between the adjacent inlet ports 7 is in contact with the discharge opening of the inlet nozzle and has cut off the passage of motive fluid into the pocket 6. When the parts have arrived at the position shown in Fig. 9, the pocket 6 has passed entirely

out of register with the pocket 14. The motive fluid, as the forward wall 8 of the pocket 6 passes the forward edge of the abutment, flows out and reacts against said forward wall 18 of the abutment to urge the rotor forward. As the pocket 6 passes this forward wall of the abutment, the motive fluid will be discharged entirely from the pocket, and while being so discharged will perform a certain amount of work by reason of the reaction, which reaction will tend to drive the rotor forward.

By reference to Figs. 6 to 10, and Figs. 4 and 5, it will be seen that by the time that one pocket commences to discharge exhausted motive fluid, the next succeeding pocket will commence to receive motive fluid, that is, the next succeeding pocket is in the position shown in Fig. 7 so that the rotor is submitted to the continuous action of the motive fluid.

In the embodiments of our invention shown in Figs. 1 and 3, there are four abutments (though we do not wish to be limited to this number) these abutments being arranged in quartering relation to each other so that a pair of abutments are disposed diametrically opposite each other. This arrangement has peculiar relation with regard to the double series of pockets 6 and acts to balance the rotor against sidewise thrust.

It will be noted that each of the inlet ports 7 has an inclined side wall which is inclined downward and toward the body of the pocket 6 and that inasmuch as the pockets 6 are arranged in staggered relation or alternately on opposite sides of the rim face, the inclination of the side walls of successive inlet ports will alternate. The pockets are so arranged upon the rotor that when motive fluid is being discharged from one nozzle into an inlet port 7 of one of the pockets 6, motive fluid will be discharged from the diametrically opposite inlet nozzle into a diametrically opposite pocket by means of the inlet port 7 thereof, and that whereas the inlet port 7 of the first named pocket will be inclined downward and toward one side of the rotor, the inlet port 7 of the diametrically opposite pocket will be inclined downward and toward the other side of the rotor, and that thus the forces exerted by the jets of motive fluid projected through the diametrically opposite nozzles will both act simultaneously toward the middle plane of the rotor, thus preventing the rotor from being subjected to sidewise thrusts and perfectly balancing the rotor. Preferably the rotor will be provided with one or more pairs of series of pockets 6 so that there shall not be an odd number of series, each two series of pockets being arranged as shown in Fig. 4 so that the force of the entering jets of motive fluid tends to hold the rotor steady and so that the side-

wise thrust of one jet will be counteracted by the sidewise thrust of another jet.

While we do not wish to be limited to any particular manner of mounting the rotor and the abutments, we have shown two different forms of turbine mounting to this end. In Figs. 1 and 2 the stator comprises a series of arcuate casing sections 19, each section having end flanges 20. These sections abut against the ends of the abutments 11, and extending over each of the abutments 11 and supported upon the flanged ends of the sections are the caps 21 which are attached to the end flanges in any suitable manner as by means of bolts 22. Each of these caps 21 carries upon it a gland 23 of any suitable description, through which loosely passes the tubular member 13 previously referred to. This tubular member 13 forms a spindle for the corresponding abutment 11 and slides easily through the gland 23. It also forms a duct in continuation of the inlet nozzle passage 12, and each of the tubular spindles 13 is connected by means of a flexible pipe or other suitable connection 24 to a source of motive fluid.

The interior face of each cap 21 is recessed as at 25, the recess being concentric to the spindle 13, and disposed within this recess is a coil spring 26 bearing at one end against the end wall of the recess and at its other end bearing against the outer face of the abutment 11. This coil spring tends to force the abutment 11 inward against the face of the rotor. While we have shown coil springs for this purpose, we do not wish to be limited to this means of yieldingly forcing the abutment against the face of the rotor as any equivalent means for this purpose may be used.

It will be seen from Fig. 1 that the rotor is slightly less in diameter than the interior diameter of the stator or casing surrounding the rotor, that is, that there is a space between the inner faces of the sections 19 and the outer face of the rotor, and that the instant that a pocket passes the end of an abutment it is placed in communication with this space, which is designated 27. Opening into this space in the form of our invention shown in Figs. 1 and 2, are the exhaust ports 28 which may either open upon the outer face of the casing of the rotor, or which may be connected to exhaust pipes 29 by which the exhaust vapors may be carried in any desired direction. It will be noted that there is an exhaust port between each two of the abutments and that the exhaust port for each abutment is located adjacent to the casing of the next succeeding abutment. The vapor commences to exhaust as soon as the pocket containing the motive fluid passes the forward edge of the abutment, and this exhaust continues until the rear end of the pocket has passed the rear

edge of the next succeeding abutment. Thus ample time is provided for a complete discharge of the exhausted fluid. This is particularly necessary in a turbine of this character, as otherwise the pockets will remain partially filled with fluid which has done its work.

Preferably in the form of our invention shown in Figs. 1 and 2, the rotor is also incased by means of side plates 30 and 31. The shaft 3 passes through the side plate 30 and the side plates abut against the edges of the sections 19. The side plate 31 is formed at its center with a seat 32 for the shaft 3. This seat is preferably conoidal in form, and the extremity of the shaft 3 is also conoidal and bears in this conoidal seat, thus forming a step bearing for the shaft.

The plate 30 is provided with a stuffing box 33 through which the shaft 3 passes. The plates 30 and 31 are spaced apart a distance slightly greater than the width of the rim 5 so that there will be a minimum of frictional resistance between the side plates 25 and the side faces of the rotor rim.

We do not wish to be limited to the use of the circumferential sections 19 and the side plates 30 and 31 as the abutments might be used without these circumferential sections and the side plates, as illustrated in Fig. 3. In this figure, 34 designates the rotor and 35 the shaft. The rotor as before described, is formed with a relatively light web and a relatively heavy rim 36. The rotor is provided with pockets along its rim in precisely the same manner as the pockets of the rotor previously described, and as illustrated in Fig. 4. The stator is provided with a plurality of abutments 37 of precisely the same form and arrangement as the abutments 11 previously described, except that the abutments are not inclosed within a casting. Each abutment 11 is preferably formed of metal such as Babbitt metal as previously stated and is yieldingly supported against the face of the rotor, each abutment being carried by a tubular spindle 38 which is rigidly attached to the abutment and extends outward therefrom.

Surrounding the rotor is a supporting frame which also forms preferably the means whereby motive fluid is supplied to the several abutments. This frame in the embodiment of our invention shown in Fig. 3 is tubular and designated 39. At intervals around the tubular frame 39 are the unions 40. Each union is provided on one face with a stuffing box 41 into which the spindle 38 of the corresponding abutment freely passes so that the spindle can have a reciprocating movement in the stuffing box 41, the stuffing box being suitably packed to prevent the escape of steam therefrom around the spindle.

Surrounding the spindle 38 and disposed 65 between the outer face of the abutment and

the union 40 is the coil spring 42 which forces the abutment yieldingly inward against the face of the rotor in the same manner as previously described for the springs 26. It will of course be understood that each spindle extends somewhat into the stuffing box so as to compensate for any movement of the abutment. The spindles act as guides for the abutments, though we do not wish to be limited to this exact means for guiding said abutments and holding them in proper position relative to the circumference of the rotor.

The pipe which forms the frame 39 is connected at any suitable point with a conducting pipe 43 whereby steam, gas or other motive fluid may be conducted to the pipe 39 from a source of motive fluid. The stator may be mounted upon any suitable base, and we have shown for this purpose the base 44 which supports the pipe forming the frame 39 and also supports the shaft 35.

It is to be noted in this form of our invention that no distinct exhaust ports are used but that practically the whole space 90 between two abutments forms an exhaust port. As soon as a pocket on the rotor has passed the forward face of the abutment, the motive fluid will be discharged in the manner shown in Fig. 9. It is to be noted in 95 connection with Fig. 9 that the motive fluid will be deflected from the wall 8 against the face of the abutment and will therefore continue to do work by reaction.

It will be seen that a turbine constructed 100 in accordance with our invention is extremely compact and simple and is therefore capable of a great many applications to which the ordinary turbine cannot be applied. It will be seen further that the rotor 105 is perfectly balanced against sidewise thrust and that it receives the impact of the motive fluid at opposite points in its diameter, thus perfectly balancing the rotor. Furthermore, it will be seen that the number of impulses 110 received by the rotor during one revolution will depend upon the number of pockets and the number of abutments, and that the power of the turbine will depend upon the kinetic energy of the steam as it is delivered 115 against the end walls of the pockets and expands within the pockets.

It is particularly pointed out that the face of the rotor between the inlet ports 7, namely, the portion 17 (see Fig. 4) acts as 120 a cut-off. This cut-off is automatic and not dependent upon any valve gear, either complicated or simple. The point of cut-off on each turbine will depend upon the length of the inlet opening 7 with relation to the 125 pocket 6. The longer the inlet port, the longer the period of inlet; the shorter this inlet port, the quicker the cut-off. It is also to be noted that the inclined side wall of the inlet port 7 deflects the motive fluid easily 130

into the corresponding pocket 6, while the force of the jet discharged from the nozzle is directed against the front wall of the pocket and the inlet port, and that this deflection of the jet laterally tends to prevent the setting up of eddy currents within the pockets and thus secures the maximum effect of the motive fluid.

The rotor may be made from one integral casting or forging, or may be made of separate plates bolted to each other as shown in Fig. 2, in other words, with a laminated structure, and the rotor may be formed with a relatively thin solid web connecting the hub and rim, with a perforated web, or with the rims supported on spokes extending from a central hub. In some cases it will be an advantage to have the rim relatively heavy so as to increase the power of the rotor, while in other cases it may be advisable to reduce the weight of the circumference of the rotor as much as possible and increase the weight of the rotor adjacent the hub, thus reducing weight and centrifugal action. By forming the rotor of relatively thin plates bolted or otherwise attached to each other, the pockets in the rotor may be very easily formed, thus reducing the cost of constructing the rotor.

Our turbine is particularly adapted to automobiles, motor boats and for running small machinery, or for use in any position

where economy of space is a desideratum. The principle of the turbine, however, may be applied to engines of any size and horse power.

What we claim is:

1. The combination of a rotor, an abutment bearing against the rotor and having a relatively soft contact face, a fixed stop beyond the abutment, and a spring between the abutment and said stop bearing upon the back of the abutment to hold its face against the rotor. 40

2. The combination of a rotor, an abutment arranged to bear thereon and having a relatively soft face, a hollow slideable spindle carrying the abutment, and a spring coiled around the spindle and bearing upon the back of the abutment to hold the face thereof 50 against the rotor.

3. The combination of a rotor, an abutment arranged to bear thereon, a hollow slideable spindle carrying the abutment, and a spring coiled around the spindle and bearing upon the back of the abutment to hold the face thereof against the rotor. 55

In testimony whereof we affix our signatures in presence of two witnesses.
